DESIGN FOR A CRAFTSMAN'S PLANE

Sundel Doniger, New York, N. Y.

Application January 12, 1945, Serial No. 117,394

Term of patent 14 years

(Cl. D93—4)

To all whom it may concern:

Be it known that I, Sundel Doniger, a citizen of the United States, residing at New York, in the county of New York and State of New York, have invented a new, original, and ornamental Design for Craftsman's Plane, of which the following is a specification, reference being had to the accompanying drawing, forming part thereof.

In said drawing,

I claim:

The ornamental design for a craftsman's plane, as shown.

SUNDEL DONIGER.
